Inventor:

Charles L. Browne

United States Patent Office.

CHARLES L. BROWNE, OF WASHINGTON, DISTRICT OF COLUMBIA.

Letters Patent No. 77,799, dated May 12, 1868.

IMPROVEMENT IN FLAME-AERATORS.

The Schedule referred to in these Letters Patent and making part of the same.

TO ALL WHOM IT MAY CONCERN:

Be it known that I, CHARLES L. BROWNE, of the city of Washington, in the county of Washington, and District of Columbia, have invented a "Flame-Aerator," being a new and useful improvement for increasing the illuminating and heating powers of flame; and I do hereby declare that the following is a full and exact description thereof, reference being had to the accompanying drawings, making part of this specification, and to the letters of reference marked thereon.

To enable others skilled in the art to make and use my invention, I proceed to describe its construction and operation.

My invention relates to providing the burner of any flame in or attached to any device used for illuminating or heating purposes, with a vertical bar, grooved on its upper or exterior edge, which is attached to the burner, and held in the required position in the flame, by means of bands or other suitable attachment. The vertical bar is reduced to a thin or sharp edge on its interior edge or curve. By means of the groove in the vertical bar, the interior of the flame is supplied with air, and its illuminating and heating powers thereby increased without any increase in the quantity of the material from which the flame is produced.

Figure 1, in the drawings hereto annexed, and made part of the specification, represents a front view of the invention.

Figure 2, side view of the invention.

Figure 3, front view, reverse of fig. 1, illustrating operation.

Figure 4, side view, illustrating operation, and showing the division of the flame.

Figure 5, section of vertical bar at the line *a-c*, fig. 1.

Figure 6, section of vertical bar at the line *a-c*, fig. 3.

I take the burner of any device used for heating or illuminating purposes, an ordinary "bat-wing" gas-burner being selected for this illustration, and by means of the bands *b b b*, fig. 1, each of which being severed at one end, on opposite sides, from the flanges of the vertical bar *a a a*, at the points *k k*, fig. 2, I attach the device to the gas-burner *g g g*, fig. 3, so placing the vertical bar *a a a* that its interior edge or curve, *e e e*, being sharp or acute, bisects the flame *h h h* lengthwise, without obstructing its flow upward, or causing it to flare, and so that the ends or mouths *e e* of the groove *fff*, fig. 2, are below the line of combustion, as shown in fig. 3. The heat of the flame causes a vacuum in the groove *fff*, fig. 4, the ends or mouths of which, *e e*, fig. 3, being below the line of combustion, afford free entrances, into which the air rushes, as shown by the double-headed darts or arrows, and the flame, meeting above the vertical bar *a a a*, but not filling the groove, (see fig. 4,) the air follows the groove, radiating off into the interior of the flame, as shown by the single-headed darts or arrows, fig. 3. Thus the interior surfaces of the flame are supplied with air, the process of combustion rendered more thorough, and the illuminating and heating powers of the flame increased, without any increase of the material required in producing the flame.

In the construction of my invention a single piece of material may be employed. Brass is preferred, though any metal not easily fused may be used, since, being placed in the flame below the line of perfect combustion, (see fig. 3,) and owing to the constant flow of air through the groove *fff*, the material does not become very much heated.

I do not claim a slotted tube placed in the flame; but

What I do claim, and desire to secure by Letters Patent, is—

The wedge-shaped bar *a a a*, grooved on its periphery or exterior edge, and so placed on the burner that the ends or mouths of the groove are below the lowest point of combustion, substantially as and for the purposes herein described.
